UNITED STATES PATENT OFFICE.

REINHOLD SCHNEIDER, OF SHARON, PENNSYLVANIA.

CONDENSER.

No. 864,925.

Specification of Letters Patent.

Patented Sept. 3, 1907.

Application filed September 4, 1906. Serial No. 333,164.

To all whom it may concern:

Be it known that I, REINHOLD SCHNEIDER, a citizen of the United States, residing at Sharon, Pennsylvania, have invented certain new and useful Improvements 5 in Condensers, of which the following is a specification.

My present invention relates to improvements in condensers and the object of the invention is to provide such a device embodying various novel features designed for the purpose of securing increased economy 10 and efficiency.

The invention includes the special features of construction and arrangement and combination of parts hereinafter described and particularly set forth in the appended claims.

15 A condenser embodying my improvements is shown in the accompanying drawings, in which,

Figure 1 is a sectional elevation. Fig. 2 a sectional plan. Fig. 3 a section on line A—A of Fig. 1, and Fig. 4 a sectional detail.

20 Referring to reference characters to this drawing, the numeral 1 designates the exhaust pipe leading from the engine whose steam is to be condensed. This has one branch communicating with the condenser body 2, and another branch 33 forming a free exhaust pipe

25 which is provided with any suitable form of automatic valve indicated at 32 which is opened when the condenser is disconnected from the exhaust. The condenser body 2 may conveniently be made with its main portion of cylindrical form and with tapered or contracted bottom and top as indicated at 5 and 7.

30 The exhaust pipe 1 communicates by its lateral branch 1^a with an annular chamber 35 completely encircling the condenser body or drum and communicating with the interior thereof by a plurality of vertically elongated apertures 35^a as shown. At the right hand side of the chamber 35 is shown a small section of pipe 1^b which is to indicate that when desired the exhaust of more than one engine may be connected with a single condenser. At its lower end the condenser body or drum communicates 40 by a pipe 6 with the hot well 23.

At 12 is shown a storage regulating and separating tank for water and air, from the side of which, near the lower end leads a pipe 8 for supplying spray water to the condenser. This spray water strikes upon a centrally 45 arranged deflecting or baffle plate 34; preferably provided with an annular flange 34^a, and falling over the edge of this strikes upon a second annular baffle plate 3 located just above the elongated steam inlet openings through which the steam enters in radially converging 50 jets. Below these openings is a third central baffle plate 4 arranged directly beneath the central opening of the plate 3. Within the valve chamber 9 of the pipe 8 is a valve 10 having an operating lever 11 designed to be operated in connection with the steam 55 throttle in the manner described in Letters Patent of the United States granted to me on the 5th day of

December 1905 and numbered 806,368. The tank 12 is supplied with water from a supply pipe leading from any suitable source of supply, as for instance the ordinary feed water pump, (not shown) the pipe leading into the bottom of the tank and being provided with an air separating nozzle as shown.

At 18 is shown a pipe which has one branch 15 connected with the top of the storage tank and another pipe 17 connected with the top of the condenser body 7, 60 its end 22 depending within an air separating chamber 19. This chamber is connected to the upper part of the storage tank 12 by a connection 14 and has an overflow or return pipe 21 leading from its lower end to the hot well. Its upper end is connected by a pipe 20 to 70 the ordinary dry vacuum pump (not shown).

The exhaust pipe 1 is provided with a nozzle 25 for a drain valve 26 under pressure of a spring 27. The valve stem 28 is provided with an elongated slot 29 which is engaged by one end of a lever 30 connected to 75 a rod or the like 31 leading to the engine pulley whereby the engineer may operate the drain valve positively, said valve operating automatically when the end of the lever is in neutral position or midway of the ends of the slot.

Having thus described the construction and arrangement of parts of my condenser I will briefly set forth the functions of the various parts and the advantages thereof.

The annular inlet channel by which the exhaust 85 steam is discharged into condenser concentrically and is brought in contact with the spray from the lower spray plate, in form of a uniform steam spray, avoids a one sided steam current, which requires more spray water and more vacuum pump capacity. 90

By the arrangement and shape of the spray plates, the upper one reverses the flow of water forming thus a paraboloid by the down coming water, which the up-coming steam and air have to penetrate radially from inside to outside. The intermediate spray plate on 95 which the water falls causes the water to spray on the up-coming steam on the inside and on the outside on the inside of the condenser body; while the water coming down from the intermediate spray plate in the shape of the inner part of a paraboloid of annular horizontal 100 section through which the steam is forced to pass concentric from the outside toward the center, the exhaust steam being at the same time subject to the action of the spray effect, caused by the lower spray plate. It is this spray-like injection of the steam and 105 the zigzag way it is forced to take, by the arrangement and form of spray plates, which guarantees a thorough mixture of the exhaust steam and spray water, requiring thus the least amount of spray water, while at the same time the highest possible vacuum is attained. 110

The storage tank 12 furnishes a maximum quantity of water at the disposal of the engineer, which is always

replaced while the engine runs on light loads, by means of valve 9 which is intended to be operated automatically whenever the throttle valve lever is operated, as in my patent above referred to. This is particularly 5 intended for reversing engines and engines working with a great change in power and steam consumption. It also gives a constant head of resistance to the pump furnishing the cold water for condensing the exhaust steam. This constant head is the agent for acting upon 10 the pump motor regulating device. It may be a steam turbine pump, electric motor or steam engine driven pump. It also enables me to separate the cold air from the water used for condensing the steam, before the water enters the condenser, drawing thus the air off 15 before it is heated in the condenser, which would require a larger vacuum pump. Nozzle 13 with slots is intended to help to force the air away from the opening leading into condenser and bring it all to the top where it is drawn off through nozzle 15 which is in connection 20 with the dry vacuum pump. It also serves to conduct all condensation matter coming from vacuum suction line through the tank overflow into hot well.

The automatic drain and positively operated valve will open automatically if engine and vacuum pump, or 25 the pump furnishing the water for condensing the exhaust steam is stopped, or if the engines and all pumps are stopped, that is, the condensing plant. But there is always a certain amount of steam leaking through the engine throttle valve, which will finally condense 30 in the exhaust pipe. Also vapor in the condenser and vapor coming from hot well will precipitate in exhaust pipe and if the engines are idle, for any length of time, the horizontal part of exhaust pipe will partly, or may fill completely, with such condensation water, which, 35 if the engine is started up again, is drawn into cylinders and since it cannot escape all through exhaust port during the return stroke on account of overlap of engine valve, it will either break the engine piston or cylinder head and may break up the engine complete.

40 The application of the automatic valve makes this impossible, as the valve will open directly after the vacuum is broken through one or the other pump breaking down or when the engines and condenser are set still.

This valve is also intended to be operated by the engineer from the pulpit for blowing out the exhaust pipe 45 and for reasons of inspection.

Having thus described my invention, what I claim is:—

1. In combination, a condenser body having equidistant annularly arranged inlet openings for the exhaust 50 steam, a water supply pipe at the upper end of said body, a centrally arranged baffle plate beneath said pipe, and above said openings, and a baffle plate below said inlet openings.

2. In combination, a condenser body having annularly 55 arranged inlet openings for the exhaust steam, a water supply pipe at the upper end of said body, a centrally arranged baffle plate beneath said pipe, an annularly arranged baffle plate beneath said first named plate and above the steam inlet openings, and a third and centrally arranged baffle plate below said openings.

3. The combination with a condenser having means for admitting exhaust steam thereto, of an elevated water storage tank, means for feeding water from said storage tank and spraying it upon the steam in the condenser and 60 an overflow pipe to maintain a constant head for regulating the water pressure in the feed pipe and the speed of the pump, motor or engine.

4. In combination, a condenser body for receiving exhaust steam, a storage tank elevated above the level of 70 the condenser body and having a connection for supplying spray water to said condenser body, a valve in said connection for controlling the passage of the water from the tank to the condenser body, and a water supply to said storage tank, and a vacuum pipe in communication with the upper 75 portion of said condenser body and storage tank.

5. In combination, a condenser body for receiving exhaust steam, a storage tank elevated above the level of the condenser body and connected to the other part thereof to supply spray water thereto, a water supply to 80 the lower part of said storage tank, a separator chamber having its central portion connected to the upper part of said tank, a drain pipe from the lower part of said separator, a vacuum pipe connected to the upper part of the separator, and a pipe depending into said separator below the end of the vacuum pipe and communicating with the upper part of both the condenser body and the storage tank.

In testimony whereof, I affix my signature in presence of two witnesses.

REINHOLD SCHNEIDER.
